To all whom it may concern:

Be it known that I, Theresa Valenti, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design.

The characteristic feature of my design resides in the combination on the specific dress disclosed of the pleated trimming around the neck and down the front of the blouse in association with the matching pleated bows and pleated contrasting panel down the front of the skirt.

I claim:

The ornamental design for a dress, substantially as shown and described.

THERESA VALENTI.
